US00D966299S

(12) **United States Design Patent** (10) Patent No.: **US D966,299 S**
Dobak, III et al. (45) Date of Patent: **** Oct. 11, 2022**

(54) **COMPUTER DISPLAY PANEL WITH A GRAPHICAL USER INTERFACE FOR A DERMATOLOGY REPORT**

(71) Applicant: **DermTech, Inc.**, La Jolla, CA (US)

(72) Inventors: **John Daniel Dobak, III**, La Jolla, CA (US); **Sarah Dion**, San Diego, CA (US); **Burkhard Jansen**, La Jolla, CA (US); **Jane Bue**, Vista, CA (US)

(73) Assignee: **DERMTECH, INC.**, La Jolla, CA (US)

(**) Term: **15 Years**

(21) Appl. No.: **29/770,784**

(22) Filed: **Feb. 16, 2021**

(51) LOC (13) Cl. **14-04**

(52) U.S. Cl.

USPC **D14/486**

(58) **Field of Classification Search**

USPC **D14/485-495**

(57) **CLAIM**

The ornamental design for a computer display panel with a graphical user interface for a dermatology report, as shown and described.

DESCRIPTION

FIG. 1 is a front view of a computer display panel with a graphical user interface for a dermatology report, showing our new design; and,

FIG. 2 is a front view of another embodiment of a computer display panel with a graphical user interface for a dermatology report, showing our new design.

The broken lines in the drawing represent portions of the computer display panel and the graphical user interface that form no part of the claimed design. The difference in crosshatch shading indicates a contrast of appearance and does not depict any particular color.

1 Claim, 2 Drawing Sheets

DermatTech		PLA Pigmented Lesion Assay MOLECULAR PATHOLOGY REPORT P: 866.480.4222 F: 866.266.2188 DermTech.org 11028 N Torrey Pine Road, Suite 700 La Jolla, CA 92037	
PATIENT INFORMATION			
Patient Name: Reference #: MRN #: DOB (yrs): Sex: Referring Physician: Address:	RX # / Acq ID: Body Site: Date Collected: Date Received: Date Reported: Fax Number: City/State/Zip:		
TEST RESULTS			
Gene Expression Status: Positive Risk Status: Moderate (Orange)		LINC00516: Detected PRAM16: Not Detected	
Expression of LINC00516 and/or PRAM16 is found in lesions with a histopathologic diagnosis of melanoma. If one or both of the genes are detected, the test is positive. Macro-dissection Report/Comments: The pre-surgical excision of adnexal patches containing four lesion samples. Except as noted, each patch contained tissue material which was free of obvious contamination with blood, epidermis, hair or other contaminants. Each patch had a central circle delineating the margin around the tissue material. Examination of each of the macrodissected specimen revealed that the lesional tissue material was excised at the margin. Each sample was submitted for qPCR analysis. Images of all 4 of the macrodissections are kept on file and are available for review.			
Interpretation: - LOW (GREEN): Melanoma associated gene expression: negative. Consider surveillance per standard of care. - MODERATE (ORANGE): Positive for a single gene (LINC only or PRAM16 only). Recommend biopsy and histopathologic assessment. The proportion of pigmented lesions that are histopathologically diagnosed as melanoma is lower in single gene positive samples (50% for PRAM16 only positives and 7% for LINC only positives) than in double gene positive samples. - HIGH (RED): Positive for both LINC and PRAM16 genes. Recommend biopsy and histopathologic assessment. The proportion of pigmented lesions that are histopathologically diagnosed as melanoma is higher in two gene positive samples (92% for both LINC and PRAM16 positives) than in single gene positive samples.

TEST RESULTS		
Gene Expression Status: Positive Risk Status: Moderate (Orange)		LINC00618: Detected PRAME: Not Detected
Expression of LINC00618 and/or PRAME is found in lesions with a histopathologic diagnosis of melanoma. If one or both of the genes are detected, the test is positive. Macro-dissection Report/Comments: The pre-surgical occlusive of adhesive patches containing four tissue samples. Except as noted, each patch contained tissue material which was free of obvious contamination with blood, exudate, hair or other contaminants. Each patch had a central circle delineating the margin around the tissue material. Examination of each of the macrodissected specimen revealed that the lesional tissue material was excised at the margin. Each sample was submitted for qPCR analysis. Images of all 4 of the macrodissections are kept on file and are available for review.		
Interpretation: - LOW (GREEN): Melanoma associated gene expression negative. Consider surveillance per standard of care. - MODERATE (ORANGE): Positive for a single gene (LINC only or PRAME only). Recommend biopsy and histopathologic assessment. The proportion of pigmented lesions that are histopathologically diagnosed as melanoma is lower in single gene positive samples (50% for PRAME only positives and 7% for LINC only positives) than in double gene positive samples. - HIGH (RED): Positive for both LINC and PRAME genes. Recommend biopsy and histopathologic assessment. The proportion of pigmented lesions that are histopathologically diagnosed as melanoma is higher in two gene positive samples (93% for both LINC and PRAME positives) than in single gene positive samples.
